UNITED STATES PATENT OFFICE.

HENRY F. STARRETT, OF CHICAGO, ILLINOIS, ASSIGNOR TO STARRETT MANUFACTURING COMPANY, OF CHICAGO, ILLINOIS, A CORPORATION OF ILLINOIS.

PANEL BOARD AND PANEL-BOARD CONSTRUCTION.

1,414,676.

Specification of Letters Patent. Patented May 2, 1922.

Application filed May 15, 1918. Serial No. 234,587.

To all whom it may concern:

Be it known that I, HENRY F. STARRETT, a citizen of the United States, residing at Chicago, in the county of Cook and State of Illinois, have invented new and useful Improvements in Panel Boards and Panel-Board Construction, of which the following is a full, clear, concise, and exact description, reference being had to the accompanying drawing, forming a part of this specification.

This invention relates to improvements in panel-boards and panel-board construction, and, more particularly, to that type of panel-board which is equipped with a dead front; that is, a panel-board of the type in which all the current and potential-carrying conductors are enclosed so as to prevent accidental contact therewith and consequent electrical shock.

One of the objects of my invention consists in the production of an improved and simplified means for producing a panel-board of this type and in which, with a very simple construction, a proper covering is also provided to protect the conductors and conductor-wires leading into the cabinet, which constitute the main feed-wires and the branch-circuit consumption wires.

Another object resides in an improved panel-board and cover-plate mounting, the cost of construction of which is very low, which is very speedily and efficiently assembled and mounted with the panel in the panel-box, and with which a wire-gutter around the sides of the panel-board units and a wiring space underneath the panel are obtained.

A further object resides in an improved means for mounting the cover-plate over the panel-board units, said means readily adapting itself to a simplified sealing structure, by virtue of which all the live parts of the board and all the connections can be placed under seal, and tampering therewith by others than those qualified can be readily detected and consequently avoided.

Other objects and features of this invention will become apparent from the following description and the appended claims.

For the purpose of disclosing my invention, I have illustrated one embodiment

thereof in the accompanying drawings, in which—

Fig. 1 is a front elevation of a cabinet and panel-board embodying my invention, parts being broken away to disclose more fully the interior construction;

Fig. 2 is a sectional view taken on the line 2—2 of Fig. 1;

Fig. 3 is a sectional view taken on the line 3—3 of Fig. 1;

Fig. 4 is a detail section taken on the line 4—4 of Fig. 1; and

Fig. 5 is a detail perspective of the mounting of the parts.

In the construction illustrated, I provide a cabinet or panel-board box preferably formed of sheet steel and having the sides 1 and the ends 2 bent up from the bottom 3 and provided with a flanged cover or door 4 hingedly secured to one of the sides of the box or cabinet. On the two sides and ends of the cabinet are provided suitable openings in which are connected the different wire conduits 5 and through which the various conductor wires are adapted to pass.

Mounted within the cabinet is a panel-board having an insulating base comprising two flat insulating plates 6 and 7 placed face to face together. The meeting face of one of the plates, preferably 6, is channeled to receive the bus-bars 8 of the panel-board, and these bus-bars are enclosed and concealed by the other plate 7. The ends 9 of the bus-bars are brought up through suitable openings in the plate 6 and lie flat on the front face of the plate.

The fuse receptacles for the branch circuit are all mounted on the front face 6 of the insulating base. The receptacles for each branch circuit comprise a removable unit. This unit comprises an insulating base 10 with a pair of threaded shell receiving recesses 11 within each of which is mounted a threaded fuse receiving shell 12 and a center contact 13. The center contact takes the form of a screw which extends through the insulating base 10 and engages one of the bus-bars, thereby electrically connecting the fuse receptacle with the bus-bars and removably securing the fuse receptacle unit in position on the board.

Mounted on the under side of the base are

a pair of conductor plates 14, one for each of the threaded shells. Each plate is provided with a laterally extending connecting terminal 15 carrying a branch wire binding-screw 16. The plate and threaded shell 12 are connected together and secured in place on the insulating base by means of screws 17 passing through the bottom of the shell, through the base, and engaging into the plate.

Forming a part of the panel-board, but comprising in itself a separate assembly unit, is a main line fuse unit. This unit comprises an insulating base 18 of the same width and thickness as the unit just described and mechanically connected thereto by a connector plate 19 secured to the bottom faces of the two bases by means of suitable screws 20 passing therethrough and engaging into the plate. The base 18 carries on its front face a conductor or bus-bar 21 one end of which is connected by a screw 22 with the central bus-bar of the branch wire base and the opposite end of which is provided with a suitable binding-post 23 for one of the leading-in terminals. This conductor strip is secured in position on the front face of the base 18 by suitable screws 23 which pass through the conductor plate, through the base and into nuts 24 countersunk in the rear face of the base, the countersunk opening in the base being filled with insulating material after the nut has been placed in position. The base 18 also carries a pair of main line fuse receptacles. Each receptacle is connected to one of the bus-bars 8 of the branch circuit unit and comprises a hollow cylindrical insulating base 25 having mounted therein a threaded-fuse-receiving shell 26 and a center contact in the form of a screw 27. The hollow receiving shell has mounted in its bottom and engaging therewith a conductor plate 28 which is provided with an extending ear 29 passing through a suitable opening in the side of the insulating base. The end of this ear 29 is connected with the exposed end of one of the bus-bars by the bridge-piece 30. The fuse receptacle is mechanically held in position by means of the screw 27, this screw being insulated from the bottom of the threaded shell by suitable insulating washers 31 and passing through the base of the receptacle, through a conductor plate 32, through the base 18 and into a suitable holding nut 33 countersunk in the rear face of the base, the countersunk opening being filled with suitable insulating material. The conductor plate 32 carries a binding post 34 to which one of the leading-in conductors is adapted to be connected.

The panel formed as above is mounted in the cabinet upon a pair of arch brackets 35, one at each end of the panel. The legs of these brackets are provided with outturned

ears 36 through which screws 37 pass engaging in the bottom of the cabinet or box and rigidly holding the brackets in position. The panel it will be noted is of smaller dimensions than the inside dimensions of the box, and by means of the arch brackets is spaced apart from the bottom of the box or cabinet so that ample wiring space is permitted between the bottom of the panel-board and the bottom of the box, whereby the leading-in wires may be brought into the box from any side, ample room being provided for placing the wires in the box beneath the panel. This is clearly illustrated in Fig. 1, where the main line conductors 80 are brought in from the top of the box or cabinet, and are carried along under the panel-board and connected to the main terminals at the bottom of the panel-board as disclosed.

The branch circuit conductors or wires are brought in through suitable conduits such as 5 one of which is located opposite each pair of branch circuit fuse receptacles, and are connected to the binding-posts 16 of the different branch circuit units. After all electrical connections are made a cover-plate 38, preferably formed of sheet steel and snugly fitting the box or cabinet is placed in position. This cover-plate has suitable openings formed therein coinciding with the different fuse receptacles, through which the fuse receptacles are adapted to pass, and the walls of these openings snugly fit around these receptacles so that the panel-board, and particularly the exposed conductor parts of the panel-board, are completely enclosed and protected. In other words, the cover-plate 38 forms a dead front shield to prevent any accidental contact with the live parts of the board. This cover-plate 38 is supported upon a pair of brackets 39, one at each end, the legs 40 of which are provided with in-turned lugs 41 to which the shield is secured.

Two of these diagonally-opposed upturned lugs 41, in the drawings the upper right and lower left one, are equipped with threaded bolts 42 which engage the tapped holes 43 in each of said lugs. These bolts are inserted from the under side of the lugs and thus project upwardly from the upper face of the lugs. Each of the bolts is transversely perforated, the perforations serving to receive a wire which functions as a sealing means when the cover-plate 38 has been put in place.

The brackets 39 which support the cover-plate 38 rest upon the brackets 35 which support the panel-board, being interposed between the bottom of the panel and the bracket 35. Suitable screws, such as 43', pass through the panel-board base, through the brackets 39, and engage in the bracket 35, thereby securing all these parts rigidly.

together. In assembling a unit of this type the circuit-controlling equipment is first mounted on the panel-board proper, after which the panel-board and the supporting brackets 35 and 39 are secured together, in the manner just described. The assembled unit is then secured to the bottom 3 of the metallic housing or enclosure, by means of the screws 37.

- 10 In the installation of the unit, the main circuit, conductors, such as 44, and the branch circuit conductors, such as 45, are next wired in place and secured to their respective connecting terminals. When the 15 panel unit has thus been completely wired, the cover-plate 38 is slipped into place over the circuit-controlling apparatus mounted on the panel-board, perforations in the cover-plate 38 permitting the projection of 20 the securing bolt 42 therethrough. To secure the cover-plate in place, suitable nuts, such as 46, are then placed in position on the protruding securing bolts. These bolts in the illustration described secure the upper right and lower left corners of the cover-plate, and the upper left and lower right corners of the cover-plate are secured to the inturned lugs 41 by means of screws, such as 47 which engage in the tapped holes 43. 25 Obviously, in a long panel, intermediate supporting brackets properly position between the two end supporting brackets shown in the illustration, secured to the panel and to the housing and cover-plate in 30 a like manner, will be used.

When the cover-plate has thus been secured over the panel unit, a sealing wire 48 is threaded through the perforation in each of the bolts 42, and this wire is properly sealed, as indicated at 49.

It will be evident from the preceding that, in order to obtain access to the connecting terminals and wiring of the panel-board, it is merely necessary to remove the two screws 45 47, break the seals 49, and remove the wire 48, and then remove the nuts 46, following which the dead-front cover-plate 38 can be readily lifted out of the cabinet and all the 50 wiring and connection terminals will be exposed to view.

Access to the wiring and connection terminals is absolutely impossible without removing the cover-plate, and, since this cover-plate cannot be removed without breaking the seals, it follows that it will be impossible without detection to tamper with the connections of the panel-board except by properly authorized parties.

For the purpose of properly designating the various circuit connections and wires of the panel-board, I prefer to place on the front face of the cover-plate, opposite each one of the branch circuit fuse receptacle units, a card-holder such as 50, which is 55 adapted to carry a number-card on which

can be suitably inscribed any information desired regarding the wiring and circuit connections. This information is especially desirable in connection with the tracing and replacing of blown fuses and any contemplated rewiring of the board. 70

Obviously, this invention is not limited to the specific embodiment thereof herein illustrated and described, but is capable of many variations and applications within the spirit 75 and scope of the invention pointed out in the appended claims.

What I claim is new and desire to secure by Letters Patent is:

1. A panel-board construction comprising, 80 in combination, a panel-box enclosure, a panel-board unit, circuit-controlling apparatus carried thereby, a cover-plate for said panel-board unit, a bracket for mounting said unit in said enclosure and a second 85 bracket interposed between said unit and said first bracket, said second bracket serving for mounting said cover-plate, the said cover-plate being positioned inside the said panel box enclosure and covering all the 90 wiring and terminal connections associated with the panel-board, said brackets and panel-board unit being assembled as a physical entity, and means whereby said entity can be quickly and easily mounted in and 95 removed from said panel-box enclosure.

2. A panel-board construction comprising, 100 in combination, an enclosing metallic housing and a panel-board unit carrying circuit-controlling equipment, a pair of U-shaped brackets mounted back to back and secured to said panel-board unit, means associated with one of said brackets for securing the unit in the metallic housing, a dead front cover-plate for said panel, and means associated with the other bracket for securing said dead-front cover-plate in said housing. 105

3. A panel-board construction comprising, 110 in combination, an enclosing panel-box housing, a panel-board unit, circuit-controlling apparatus carried by said unit, a dead-front cover-plate for said panel-board unit, a pair of U-shaped mounting brackets placed back to back and secured to said panel unit, means associated with one of said mounting 115 brackets to secure the same to said metallic housing, means associated with the other mounting bracket for mounting said cover-plate, and a sealing means associated with said last-mentioned means, which sealing means must be broken in order to remove said cover-plate and obtain access to the 120 circuit-connections on said panel-board.

4. A panel-board construction comprising, 125 in combination, a metallic enclosing housing or panel-box, a panel unit, circuit-controlling equipment mounted on said panel unit, two U-shaped brackets mounted back to back and secured to said panel unit, supporting means associated with one of said brackets 130

- for securing said unit in said panel-box, in-
5 turned lugs associated with the other bracket
for mounting said cover-plate, means for
securing said cover-plate to said inturned
5 lugs, and a sealing means associated with
said last-mentioned means which must be
broken to remove said cover-plate.
6. A panel-board construction comprising,
in combination, a panel-box, a panel unit,
0 circuit-controlling equipment mounted on
said panel unit, a coverplate, a plurality of
pairs of U-shaped brackets mounted back to
back and secured to said panel units, means
15 for securing one of said brackets to said
panel-box and so positioning said panel unit
with respect to the side walls of said panel-
box that a wiring gutter will be formed
about the edges of said panel unit and a
20 wiring space will intervene between the bot-
tom of the panel-box and said panel-unit,
and means associated with said other bracket
for mounting said cover-plate thereon where-
by the wiring of said panel unit and the
25 terminals of said circuit-controlling equip-
ment will be completely covered by said
cover-plate.
7. A dead front panel-board construction
comprising a panel box having sides and bot-
30 tom and having openings in the sides for the
connection of conduits and the passage of
main and branch circuit connecting wires,
a pair of arch brackets mounted at each end
35 of said box, a panel-board mounted on said
brackets and comprising a substantially flat
insulating base, a plurality of fuse recep-
tacles and exposed binding post terminals
40 mounted on the front face of said base, and a
dead front shield removably mounted in and
snugly fitting said box on said brackets over
45 said panel-board, having openings coincid-
ing with said fuse receptacles to permit the
fuse receptacles to project therethrough, said
plate completely covering the panel-board
50 and all exposed electrical parts thereof and
being spaced apart from the front face of
the board.
8. A dead front panel-board construction
comprising a panel box having sides and bot-
55 tom and having openings in the sides for the
connection of conduits and the passage of
main and branch circuit connecting wires, a
panel-board mounted in said box compris-
60 ing a substantially flat insulating base, a
plurality of fuse receptacles and exposed
binding terminals mounted on the front face
of said base, a pair of brackets at each end
65 of said board, a dead front shield removably
mounted upon said brackets and being
spaced apart thereby from the front face of
said panel-board, said shield snugly fitting
70 said box over the panel-board and having
openings coinciding with said fuse recep-
tacles to permit the fuse receptacles to pro-
ject therethrough and completely covering
75 the panel-board and all exposed electrical
parts thereof.
9. A dead front panel-board construction,
comprising a panel-board enclosing struc-
80 ture having sides and ends and openings
therein for the passage of main and branch
conductor wires, a panel-board in said struc-
ture comprising a substantially flat insulating
85 base, a plurality of fuse receptacles and ex-
posed binding terminals mounted on the front
face of said base, and a dead front shield re-
movably mounted in and snugly fitting said
90 structure over said panel-board, having
openings coinciding with the fuse recep-
tacles to permit the fuse receptacles to pro-
ject therethrough, said plate completely cov-
95 ering the panel-board and all exposed elec-
trical parts thereof and being spaced apart
from the front face of the panel-board. 100
10. A dead front panel-board construc-
tion, comprising a panel-board enclosing
structures having sides and ends and open-
105 ings therein for the passage of main and
branch conductor wires, a panel-board in
said structure comprising a substantially
flat insulating base, a plurality of circuit-
controlling appliances and exposed binding
110 terminals mounted on the front face of said
base, and a dead front shield removably
mounted in and snugly fitting said struc-
ture over said panel-board, having openings
115

therein to permit the circuit-controlling appliances to project therethrough, said plate completely covering said panel-board and being spaced apart from the front face of the said panel-board, brackets for mounting said panel-board and for mounting said dead front shield, said brackets and panel-board being assembled as a physical entity, the brackets for mounting said panel-board providing a wiring space between the bottom face of said panel-board and the top face of the bottom of said enclosing structure, and means whereby said entity can be quickly and easily mounted in and removed from said panel-box enclosure.

11. A panel-board construction comprising, in combination, a panel-box enclosure, a panel-board unit, circuit-controlling apparatus carried thereby, a cover-plate for said

panel-board unit, a bracket for mounting said unit in said enclosure, said brackets providing a wiring space between the bottom face of said panel-board unit and the top face of the bottom of said panel-box enclosure, and a second bracket interconnected to said first bracket, said second bracket serving for mounting said cover-plate, said cover-plate being positioned inside the said panel-box enclosure and covering all the wiring and terminal connections associated with the panel-board, said brackets and panel-board unit being assembled as a physical entity, and means whereby said entity can be quickly and easily mounted in and removed from said panel-box enclosure.

In witness whereof, I have hereunto subscribed my name.

HENRY F. STARRETT.
